UNITED STATES PATENT OFFICE.

JOSEPH HALL, OF LEEDS, ENGLAND.

MACHINE FOR TREATING HIDES, SKINS, OR LEATHER.

SPECIFICATION forming part of Letters Patent No. 618,869, dated February 7, 1899.

Application filed October 4, 1898. Serial No. 692,611. (No model.)

To all whom it may concern:

Be it known that I, JOSEPH HALL, a subject of the Queen of Great Britain, residing at Leeds, in the county of York, England, 5 have invented certain new and useful Improvements in Machines for Treating Hides, Skins, or Leather, of which the following is a specification.

My invention has relation to a machine especially adapted for those operations upon hides, skins, and leather technically known as "softening," "setting out," or "putting out," although it may also be adapted for other and analogous operations, and in such 15 connection it relates particularly to the construction and arrangement of such a machine.

Heretofore in machines of the class or type known as "softening," "setting out," or 20 "putting-out" machines, as illustrated in Letters Patent No. 599,831, granted to me under date of February 22, 1898, the work was supported upon a vertically-arranged frame or table, and during the upward movement of said frame or table the work was presented to two working rolls or cylinders, one 25 on either side of the table.

In the machine of the present specification the parts have been reorganized, rearranged, 30 and simplified, so that but one working roll or cylinder is required and the work is supported on a horizontally-arranged apron or flexible bed which is vertically movable to present the work to the roll and is adapted to 35 be reciprocated longitudinally to cause the roll to act upon the work from end to end.

My invention, stated in general terms, consists of a machine for treating hides, skins, or leather constructed and arranged in sub- 40 stantially the manner hereinafter described and claimed.

The nature and scope of my invention will be more fully understood from the following description when taken in connection with 45 the accompanying drawings, forming part hereof, in which—

Figure 1 is an end elevational view of a machine embodying main features of my invention. Fig. 2 is a top or plan view of the 50 machine. Fig. 3 is a side elevational view of the machine. Fig. 4 is a longitudinal sectional view on the line $x-x$ of Fig. 2, and Fig.

5 is a similar view of a modified form of machine wherein the flexible bed is supported upon two rollers in fixed bearings and above 55 one or more perforated pipes from which air under pressure escapes to sustain the bed in operative position.

Referring to the drawings, b represent the side frames of the machine, the top portions 60 of which form bearings for a shaft a^6 , carrying the working roll or cylinder a . On the shaft a^6 , which forms the power-shaft of the machine, are located the fast and loose pulleys a^1 and a^2 , by means of which the machine 65 may be brought into and out of operation. On the shaft a^6 is also located a drum or pulley b^4 , which is connected by a straight belt b^5 and a crossed belt b^6 with two loose pulleys b^7 and b^8 on a shaft e , having bearings 70 in the lower portion of the side frames b . Between the two loose pulleys b^7 and b^8 on the shaft e is located a fast pulley b^9 , on which is adapted to be shifted, as hereinafter described, either the straight belt b^5 or crossed 75 belt b^6 , whereby the shaft e will be rotated in one direction or the other, according to which belt is on the fast pulley.

The side frames b are grooved, as at b^{10} , to receive and guide a horizontally-arranged 80 frame or table b' , carrying at its ends the uprights or standards b^2 and b^3 , over which is drawn an apron or flexible bed k . One end of the apron k is by preference secured to hooks k' on the table b' , while the other end 85 is attached directly to the upright or standard b^3 . The table or frame b' and the apron k are given a reciprocating movement below the work-roll a by means of the following preferred mechanism: On the shaft e is secured 90 a pinion e' , which gears with a rack m , secured to the base of the table b' , and thereby moves the table in a horizontal plane according to the direction in which the shaft e rotates. As previously explained, the shaft e rotates first 95 in one direction and then in the opposite direction, according to whether the straight or crossed belt is on the fixed pulley b^9 of shaft e . Hence the movement of shaft e through pinion e' and rack m imparts a reciprocating 100 movement to the table b' and its apron k .

The automatic shifting of the straight and crossed belts is accomplished, preferably, by the movement of the table or frame b' in the

following manner: The belts b^5 and b^6 are moved by belt-forks f^{11} and f^{12} , carried by a rod or bar f^2 . Pivoted, as at f , to the base of the machine is a weighted lever f' , in the 5 slot f^{13} of which extends a pin or projection f^{14} of the rod or bar f^2 . The bar or rod f^2 has a projection or pin f^3 intermediate of its ends, which projection is adapted normally to come into contact with either of the opposite-inclined tappets f^4 or f^5 , carried by the 10 table b' and to be shifted with the bar f^2 in one direction or the other by said table, according as either tappet f^4 or f^5 engages said pin f^3 . The bar f^2 extends beyond the projection f^3 , and is provided with a collar f^6 , which is adapted to be engaged by the forked end of a rod f^7 , pivoted to a hand-lever d' and guided in a lug f^8 of the frame b , so that when the lever d' is moved in one direction 15 the forked rod f^7 will engage the collar f^6 to prevent movement of the belt-shifting bar f^2 .

Above the table b' and below the apron or flexible bed k is located a vertically-movable frame or support c , in which are carried the 20 rollers c' , the shafts of which have spring-bearings c^2 , arranged in boxes c^3 , which are guided vertically in the side frames b of the machine. The frame or support c is adapted to be elevated and depressed in the following 25 preferred manner: The hand-lever d' is fixed to a shaft d , adapted to rock in suitable bearings in the side frames b . This rock-shaft d is also provided with the two arms d^2 , each of which is connected by a suitable link d^3 30 with two similar arms d^4 and d^5 , carried by the shafts d^6 and d^7 , having bearings in the side frames b directly below the support or frame c . The upper ends of the arms d^4 and d^5 are toggled to the support or frame c by 35 means of the links d^8 and d^9 , as clearly illustrated in Fig. 4. When now the hand-lever d' is operated to draw the forked rod f^7 out of engagement with the belt-shifting bar f^2 , the arm d^2 and link d^3 will throw the 40 support c and its rollers c' upward to the position shown in Fig. 4, in which position the apron and the work are brought by the rollers c' into such relationship with the work-roll a that approximately one-third of the 45 periphery of said work-roll can act upon the work. When the hand-lever d' is shifted in the opposite direction to bring the forked rod f^7 into engagement with the belt-shifting bar f^2 , the support c and rollers c' are lowered and the 50 apron or flexible bed k falls away from the working roll a . In this latter position of the apron the work may be removed or replaced. To place the work upon the apron, one end of it is brought over the projection b^3 and held 55 there by a nipping-bar g , which is supported by vertical rods g' , the lower ends of which carry the rolls g^2 , which ride upon the links d^3 . When the links d^3 are lowered to lower 60 the support c and the rollers c' , the rods g' and rolls g^2 drop to bring the nipping-bar g 65

away from the under side of the projection b^3 . In this position of the nipping-bar g the end of the work is inserted between the nipping-bar g and projection b^3 , and when the machine is again put into operation by the 70 release of the shifting-bar f^2 and the elevation of the support c and rollers c' the link d^3 is elevated and raises the nipping-bar g to pinch or clamp the end of the work to the projection b^3 . 75

In Fig. 5 a modified form of the machine is shown wherein the rollers c' are not supported in spring-bearings, but are fixed against vertical movement. In this form the flexible bed k passes over the two rollers c' and over one 80 or more air-pipes m , located intermediate of the rollers and perforated at the upper edge or edges, as at m' . Air under pressure is forced into these pipes m and escapes through the perforations m' , thus supporting the flexible bed in operative position and yet permitting it to yield in a vertical direction. If desired, the apron k may be entirely dispensed with in this form and the hide or skin may be sustained upon the rollers c' in operative position with respect to the cylinder a by means of the air-blast from the pipes m . 85

Having thus described the nature and objects of my invention, what I claim as new, and desire to secure by Letters Patent, is— 90

1. In a machine of the character described, a single working roll, a table, a flexible bed supported by said table, means for reciprocating said table below the roll, and means for elevating the flexible bed into operative 100 position with respect to said roll, substantially as and for the purposes described.

2. In a machine of the character described, a single working roll, a horizontally-arranged table, a flexible bed supported by said table 105 and located below the working roll, means for reciprocating said table, mechanism for elevating said flexible bed during the reciprocation of the table so as to present the bed to the periphery of the working roll, and 110 mechanism for securing the work to the bed during the reciprocation of the table, substantially as and for the purposes described.

3. In a machine of the character described, a working roll, a table, means for reciprocating the table beneath the working roll, an apron supported by said table, two rollers located below the apron and on either side of the working roll, and means for elevating 115 said rolls to present the apron in operative 120 position to the working roll during the reciprocation of said table, substantially as and for the purposes described.

In testimony whereof I have hereunto set my signature in the presence of two subscribers 125 and witnesses.

JOSEPH HALL.
